METHOD AND APPARATUS FOR MANUFACTURING UPHOLSTERED PANELS

Allister S. Mitchell, Detroit, Mich., assignor to
National Automotive Fibres, Inc., Detroit,
Mich., a corporation of Delaware

Application July 10, 1935, Serial No. 30,757

18 Claims.

(Cl. 154—2)

This invention relates particularly to upholstery panels adapted to be used as trim-panels in automobile bodies, to an improved method of manufacturing such panels, and to improved apparatus 5 adapted to the practice of said method.

The primary object is to provide an improved upholstery panel, an economical method of manufacturing the same, and simple apparatus well adapted to the practice of said method.

10 It is known to provide, for the purpose of upholstering automobiles, trim-panels equipped with snap-fasteners which can be inserted through holes or sockets in the framework of the body of the automobile.

15 It is desirable that such upholstery panels shall be provided, between the foundation-plate of the panel and the finish-fabric which serves as a cover, with a padding-sheet, giving softness to the upholstery.

20 Upholstery panels of the character mentioned are of suitable size and contour for the space which they are to occupy; and, where necessary, openings or cut-away portions are provided. For example, upholstery panels for doors may have 25 portions cut away to conform to the contour of the lower portion of the door, and may have openings, as for example for the handle-shaft, the shaft of the window-operating mechanism, or the like. Heretofore, it has been the practice to 30 provide a relatively stiff sheet of material to serve as a foundation-plate, this sheet being cut to suitable contour and provided with necessary openings; and, where a layer of filling material has been interposed between the foundation-plate 35 and the finish-fabric, it has been common practice to employ a sheet of what is known in the trade as "blue wadding", the padding being cut or stamped by dies to give it a contour corresponding with the base-plate and to provide 40 openings corresponding with those in the base-plate. In this method of manufacture, considerable difficulty is encountered in applying the padding to the base-plate and getting it to register properly. Such method of manufacture involves 45 undue expense, and, moreover, fails to give a desirably even surface next to the cover-fabric.

In accordance with the preferred process herein described, foundation-plates having a surface 50 sprayed or coated with adhesive, are fed in succession through suitable apparatus, together with a continuous strip of cotton batting which becomes adhesively joined to the successive foundation-plates; and suction-means with which the 55 apparatus is provided serves to draw the cotton

downwardly through the openings in the plates and through the spaces between or surrounding the plates and trimmers with which the apparatus is equipped serve to trim off the cotton which is thus drawn downwardly about the edges of the 5 plates.

This method provides an upholstery panel comprising a panel-plate, and a layer of cotton batting, or other soft unwoven fibre adhesively joined to one surface of the panel-plate. It has been 10 found that the padding-layer thus applied is of even thickness and presents a smooth, unruffled outer surface. Moreover, some of the cotton fibres are drawn downwardly over some of the edges of the panel-plate, thus tending to round 15 the edges of the product and aid in securing the padding in smooth, even condition upon the panel-plate.

The panel-plate, after the padding has been 20 thus applied, has a cover-fabric applied over the padding, the margins of the fabric being commonly lapped over the peripheral edge-portions of the panel-plate and cemented to the under or back surface thereof. The cover-fabric may be applied in any desired manner. It may, for example, be applied in the manner illustrated in my 25 application Ser. No. 11,527, filed March 16, 1935. The invention, in a preferred embodiment, is illustrated in the accompanying drawings, in which—

Fig. 1 is a broken side elevational view of novel 30 mechanism embodying the invention which is adapted to the practice of the improved process; Fig. 2, a plan view of the same; Fig. 3, a vertical sectional view taken as indicated at line 3 of 35 Fig. 2; Fig. 4, a broken vertical longitudinal sectional view of the machine, the feed rolls and stripper-rolls being shown in elevation, however; Fig. 5, a fragmentary view illustrating the manner in which the trimmer-roll, which is second 40 in order of operation, performs the function of trimming the cotton against the forwardly presented edges (the initial end-edge of the panel and the final edges of the perforations); Fig. 6, a broken transverse sectional view taken as indicated at line 6 of Fig. 1; and Fig. 7, a broken sectional view illustrating my improved trim-panel applied to a frame-member of an automobile body.

In the drawings illustrating the improved 50 machine, A designates a frame which may be of any suitable construction, presenting a bed A' over which the work passes; B, B' and B², sets of feed rolls, the bights of which are located at or just above the bed of the machine; C, a counter-clock- 55

wise-turning trimmer-roll, with which is associated a feed-roll C'; D, a clockwise-turning, trimmer-roll with which is associated a feed-roll D'; E, a suction-box connected with an exhaust conduit E', the top of the suction-box constituting a portion of the bed of the machine; F, a conveyor which preferably is employed for feeding the materials to the feed-rolls; G, a conveyor serving to convey the cotton-covered panel-boards 10 from the machine; H, an electric motor which drives the trimmer-rolls C and D at a high rate of speed through the medium of a belt or chain H'; I, a speed-reducing gear-set driven from the motor H, as by means of a belt or chain I', and 15 from which a belt or chain I², operating at reduced speed, serves to drive a wheel or pulley J which is fixedly mounted upon the shaft of the front roller J' of the conveyor F.

The exhaust pipe E' of the suction-box may 20 have suction applied thereto in any suitable manner, as by means of a suction fan (not shown) driven by the motor.

It will be understood that the trimmer-rolls C and D are driven directly from the motor at a high 25 rate of speed. The shaft of the trimmer-roll C is designated 1, and that of the trimmer-roll D is designated 2. As shown in Fig. 1, the rolls are geared together by gears 3, which cause the rolls to rotate in opposite directions.

30 As shown in Fig. 3, the shaft of the roller J' serves, through the medium of a belt or chain 4, to actuate the feed-rolls. The feed-rolls are connected by a system of belts or chains 5 at one side of the machine and spur-gears 6 at the other 35 side of the machine in such manner that members of each set of feed-rolls are rotated in opposite directions and in such a way as to feed the materials through the machine. It will be understood that the feed-rolls C' and D' which 40 coact with the trimmer-rolls C and D, rotate at the same speed as the sets of feed-rollers B, B' and B². The final conveyor G is actuated from one of the rear feed-rolls B' by means of a belt or chain 7.

45 The surfaces of the sets of feed-rolls B, B' and B² may be of any suitable material. They may, for example, be of rubber adapted to yield slightly.

The trimmer-rollers C and D preferably are 50 covered with wire-bristle cloth, as indicated at 8, the bristles being set so as to incline rearwardly with respect to the direction of rotation. The surfaces of the coating feed rolls C' and D' may be of any suitable material. Preferably they 55 are covered with wire-bristle cloth, the bristles having a rearward inclination at the bight. The use of wire bristles on the feed-rolls proper tends to give a more positive forward feed of the materials while they are being operated upon by the 60 trimmer-rolls.

The suction-box E is shown provided with cross-members 9 and 10 which support rigidly secured metal plates 9^a and 10^a interposed between the rolls, as shown in Fig. 4. An additional transverse plate 11 forming a part of the bed is shown 65 at the left of the trimmer-roll D in Fig. 4. Between the plates and also between the plate 9^a and the front wall 12 of the suction-box are openings through which air may be drawn downwardly 70 through the suction-box.

The machine enables panels of various forms to be fed through and have a layer of cotton batting, for example, applied thereto. In Fig. 2, two series of door-panels 13 are shown as being 75 fed through the machine; and, in addition, small

panels 14 and 15 (located in the cut-away portions of the door-panels) are being fed through the machine. The panel-board 13 is shown provided with openings 13^a. It is noted, also, that the panel-boards are spaced with relation to each other. This, in effect, is the same as perforations through the panel-board, since the cotton can be drawn downwardly through the spaces and brought within the range of action of the trimmer-rolls C and D.

The cotton preferably is supplied to the machine from a roll K supported on a core K' which is vertically movable in standards K² which flank the conveyor F. As shown, the strip 16 of cotton batting is drawn from the roll K by the feed-rolls. In turn, the roll of batting operates, in conjunction with the conveyor F, to convey the panel-boards 13, 14 and 15 to the feed-rolls.

In the preferred practice of the process, the panel-boards, having their upper surfaces sprayed 20 with adhesive, are placed on the conveyor F, and thereby carried between the roll of batting and the conveyor and thence forwardly to the feed-rolls. In passing between the sets of feed-rolls B and B', the cotton padding is evenly ironed 25 upon the panel-boards as they pass in succession through the machine. As the work passes over the suction-box E, the suction is sufficient to rupture the cotton at all points not supported by the panel-boards, and the projecting portions of 30 the cotton are drawn downwardly about the edges of the panel boards into the suction-box. As the downwardly depending portions of the cotton pass over the trimmer-roll C, that roll operates to trim away portions of the cotton, these portions then 35 passing through the suction-duct E' to a suitable collector (not shown). The trimmer-roll C operates to effectively trim, against any rearwardly presented edges of the panel-boards, the depending portions of cotton. Thus, the trimmer-roll C acts particularly with respect to the rearwardly presented front walls of the perforations and the rearwardly presented rear edges of the panel-boards to trim the cotton with respect to said edges.

40 As the work progresses through the machine, the trimmer-roll D operates particularly to trim the depending cotton against the forwardly presented edges of the panel-boards, that is, the front edges of the panel boards and the forwardly 45 presented rear walls of the openings in the panel-boards.

The first trimmer-roll C operates to remove most of the cotton which depends over the lateral edges of the panel-boards; and this action 50 is supplemented by the action of the second trimmer-roll B as the work progresses through the machine.

In Fig. 5, the action of the second trimmer-roll (the trimmer-roll D) is illustrated, trimming the 55 cotton against the forwardly presented edge of the opening 13^a in the panel-board. It will be understood that before the work reached this point, the cotton had already been trimmed with respect to the front half of the opening 13^a by 60 the roller C' acting against the rearwardly presented edge of the opening. It will be noted that the cotton fibres are drawn downwardly about the wall of the opening, as indicated at 16^a. Thus, in effect, the cotton fibres form a lining 65 for the wall of the opening. A similar result is secured wherever the trimmer-rolls act in opposition to the forwardly presented edges or the rearwardly presented edges, as the case may be, of the panel-boards. In Fig. 2, the cut-away por- 70

tion of the panel 13 is indicated at 13^b. When the panel is passed through the machine in the direction indicated, the wall of the cut-away portion is, in effect, presented rearwardly, acting like the rearwardly presented front wall of a perforation. Both trimmers act upon the downwardly drawn cotton at the lateral edges of the panel-board, the trimmer-roll D serving to remove any bits of cotton which have not been removed by the trimmer-roll C. At the lateral edges, some of the fibres are left drawn downwardly and in effect wrapped about the lateral edges, tending to hold the margins of the cotton in position and produce a certain amount of binding of the fibres about the lateral edges of the panel-board. If desired, the mechanism may be varied to provide trimmers which will operate with respect to the lateral edges of the panel-boards very much as the trimmer-rolls C and D operate with respect to the forwardly and rearwardly presented edge-walls of the panel-boards and the openings therein.

Preferably, as stated, the trimmer-rolls C and D are equipped with wire bristles which scratch or tear the padding material bit by bit from the unwoven sheet. Thus, said rolls act to brush-trim the projecting margins of the padding material at the edges of the panel-board.

Fig. 7 illustrates one of the improved trim-panels applied to a frame-member 17 of an automobile body. Between the layer of cotton 16 and the panel-board 13 is a coating of adhesive designated 18. Applied over the padding 16 is a cover 19 of suitable finish-fabric. The fabric 19 has its margins turned about the margins of the padded panel-board and cemented to the rear surface of the panel-board by adhesive 19^a. The panel-board is shown provided near its edges with snap-fasteners 20 which may be of any suitable form and which may be secured to the trim-panel in any desired manner. In the illustration given, the spring-prongs 20a in the fastener extend through a perforation 17^a of the frame-member 17. It will be noted that the fibres of the cotton 16 are drawn downwardly about the edge of the panel-board 13, as indicated at 16^b, corresponding, in this respect, with the effect shown at the perforation 13^a in Fig. 5.

The improved method enables production to be speeded up enormously, and provides an improved product, in which the layer of padding material is very smoothly applied to the panel-board and very effectively secured thereto. In a measure, the edges of the panel-board are moderately padded and rounded. That very great economy is effected will be evident to those skilled in the art when it is remarked that it becomes unnecessary, because of the improved process, to manufacture blue wadding and dye-cut the same into pre-formed pads for application to the panel-boards. As mentioned above, difficulty is experienced in the old method, in obtaining perfect registration of the pre-cut padding sheet and the panel-board. Not only is the expense of the old method far greater, but the same uniformity in thickness and unruffled smoothness of surface adjacent the inner surface of the covering cannot be attained.

The panel-plates which are to be upholstered may be of any suitable material, such as fibre board, ply-board, or the like. Sheet metal may be employed, but is less desirable.

In a broad sense, the use of suction in the improved process utilizes pneumatic pressure for rupturing the cotton and forcing the marginal

portions downwardly about the edges of the panel-board. Accordingly, the use of pneumatic pressure, however applied, for accomplishing this result is to be regarded as an equivalent and within the scope of appended claims.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. A method of producing an upholstery panel which comprises applying pneumatic action to a panel-plate and an associated layer of fibrous padding material to force projecting portions of the padding material about the edges of the panel-plate, and removing marginal portions of the padding material.

2. A method of producing upholstery panels which comprises passing a series of panel-plates and an overlying continuous strip of padding material within the range of a pneumatic device and drawing portions of the padding material downwardly about the edges of the panel-plates, and trimming away the projecting portions of the padding material.

3. A method of producing upholstery panels which comprises adhesively joining a series of panel plates and a layer of padding material, subjecting them to suction to rupture the padding material and draw portions of the padding material about the edges of the panel-plates, and removing the projecting portions of the padding material.

4. In the manufacture of upholstery panels, a method which comprises: passing over a suction device a series of panel-plates and an overlying continuous sheet of unwoven padding material, and by means of suction rupturing the padding material and drawing portions of the padding material about the edges of the panel-plates, and trimming away projecting portions of the padding material.

5. A method of producing upholstered panels which comprises feeding a series of adhesive-coated panel-plates and an overlying continuous sheet of padding material through compressing means and then over a suction-device; applying suction to rupture the padding material and draw portions thereof downwardly about the edges of the panel-plates; and trimming away projecting portions of the padding material.

6. A method as specified in claim 4, characterized by performing the trimming action by rotary trimmers acting against opposed edges of the panel-plates.

7. A method of producing panels which comprises feeding a series of adhesive-coated panel-plates and a continuous strip of batting between compression-rolls, the batting being taken from a roll and acting in conjunction with a conveyor to feed the panel-plates to the compression-rolls; passing the work over a suction bed and applying suction to rupture the batting and draw portions thereof downwardly about the edges of the panel-plates; and trimming the depending portions of the batting and conveying the trimmed portions away by suction.

8. Apparatus for the purpose set forth, comprising a suction device; trimmers associated therewith; and means for feeding a series of panel-plates and an associated layer of batting

across the suction-device and within the range of said trimmers.

9. Apparatus for the purpose set forth, comprising a suction-bed; trimmers therein; and means for feeding a continuous sheet of batting and an underlying series of panel-plates to and across said bed, said means comprising a conveyor for advancing the panel-plates and a superposed source of supply for the continuous sheet of batting.

10. Apparatus for the purpose set forth, comprising a suction-bed; means for applying suction thereto; trimmers associated with said suction-bed; compression feed-rolls between which the materials pass on their way to the trimmers; a conveyor for feeding adhesive-coated panel-plates; and a source of supply from which the layer of batting is placed upon the panel-plates as they are forwarded in succession by said conveyor to said compression-rolls.

11. Apparatus for the purpose set forth, comprising a bed equipped with a suction-device; bristle-equipped trimmers mounted in said suction-device below said bed; and means for feeding over the suction-device and trimmers a series of panel-plates and an overlying continuous sheet of padding material.

12. Apparatus for the manufacture of upholstery-panels comprising: a suction-device; trimmer-rolls associated with the mouth of said suction-device and equipped with means for actuating them at relatively high speed; feed-rolls, including rolls opposed to said trimmer-rolls, said feed-rolls operating at slower speed; and means for supplying a continuous sheet of batting to the feed-rolls.

13. Apparatus for the manufacture of upholstery-panels comprising: a bed equipped with feed-rolls and with trimming-rolls; means for supplying a continuous sheet of batting and a series of panel-boards to said feed-rolls with said panel-boards at the side of said sheet which is towards the trimming-rolls; and means for forcing

cotton from said sheet downwardly about the edges of the panel-boards to bring said cotton within the action of said trimming-rolls.

14. In apparatus for use in producing upholstered panels comprising a panel-plate and batting applied to a surface thereof: a power-driven permanent conveyor serving to support a plurality of pre-formed panel-plates in series and advance said plates; and means for supplying a continuous sheet of batting, such as cotton batting, over and compressing the same upon the advancing panel-plates.

15. Apparatus as specified in claim 14, in which said conveyor is an endless conveyor having a panel-loading end-portion disposed back of the zone of application of the batting to the advancing panel-plates.

16. Apparatus as specified in claim 14, in which said conveyor is an endless conveyor having a panel-loading end-portion disposed back of the zone of application of the batting to the advancing panel-plates, and in which the compressing means includes compression-rolls receiving the batting and underlying panels from said endless conveyor.

17. In the manufacture of upholstery panels, the steps which comprise: feeding a continuous sheet of unwoven fibrous padding material; adhesively applying a series of pre-formed panel-plates thereto; and afterwards rupturing said sheet of padding material between adjacent edges of said panel-plates and brush-trimming the padding material at the edges of said panel-plates.

18. In the manufacture of upholstered panels, the steps which comprise: feeding a continuous sheet of unwoven fibrous padding material; applying a series of pre-formed panel-plates thereto; and then rupturing said sheet of padding-material between the panel-plates and brush-trimming projecting portions of said padding-material at the edges of said panel-plates.

ALLISTER S. MITCHELL.
